United States Patent Office

Des. 221,972

Patented Sept. 21, 1971

221,972

COMBINED TUMBLER AND SUPPORTING NECKLACE THEREFOR

Edward T. Kennedy, Wheeling, W. Va., assignor to
Fostoria Glass Company, Moundsville, W. Va.

Continuation-in-part of design application Ser. No.
19,668, Oct. 22, 1969. This application June 9,
1970, Ser. No. 23,389

Term of patent 14 years

Int. Cl. D7—01

U.S. Cl. D36—8

FIG. 3

FIG. 4

FIG. 5

FIG. 6

FIG. 7

FIG. 9

FIG. 8

FIG. 10

FIG. 1 is a front elevational view of a combined tumbler and supporting necklace therefor showing my new design.

FIG. 2 is a side elevation thereof.

FIG. 3 is a rear elevation.

FIG. 4 is a top plan view.

FIG. 5 is a bottom plan view.

FIG. 6 is a front elevational view of a combined tumbler and supporting necklace therefor showing another form of my new design.

FIG. 7 is a side elevation thereof.

FIG. 8 is a rear elevation.

FIG. 9 is a top plan view.

FIG. 10 is a bottom plan view.

It is understood that the chain member is continuous in the path indicated by the dashed lines in FIGS. 6-10.

This is a continuation-in-part of my application D. 19,668 of Oct. 22, 1969, now abandoned.

I claim:

The ornamental design for a combined tumbler and supporting necklace therefor, substantially as shown and described.
